UNITED STATES PATENT OFFICE.

ORLANDO C. FETZER, OF ORRVILLE, OHIO.

FOOT REST.

Application filed October 21, 1922. Serial No. 596,050.

To all whom it may concern:

Be it known that I, ORLANDO C. FETZER, a citizen of the United States, residing at Orrville, in the county of Wayne and State 5 of Ohio, have invented certain new and useful Improvements in Foot Rests, of which the following is a specification.

The present invention relates to foot rests, more particularly adapted for use in connection with the accelerator pedals used in automobiles for controlling the gas throttle.

The principal object of the invention is to provide a foot rest that supports the foot during the entire stroke of the accelerator.

Another important object of the invention is to provide a foot rest of this nature which is attractively and neatly designed, capable of being readily fastened adjacent the accelerator pedal without the necessity of mar-

20 ring the foot board of the automobile, to provide the foot rest with a wide base so that it will rest very rigidly upon the foot board and the foot engaging face of the foot rest is inclined so as to eliminate the side 25 strain on the foot when pressing down upon the accelerator.

A still further object of the invention is to generally improve upon devices of this nature by providing a structure which will 30 be simple and efficient, reliable in operation, inexpensive to manufacture, durable, and well adapted to the purpose for which it is designed.

With the above and other objects in view 35 as will appear as the description progresses, the invention resides in certain novel features of construction, and the combination and arrangement of parts as will be herein-after more fully described and claimed.

In the drawing—

Figure 1 is a perspective of the foot rest showing the same adjacent an accelerator pedal,

Figure 2 is an elevation of the foot rest,

Figure 3 is a top plan thereof showing the body thinner than is illustrated in Figures 1 and 2, and

Figure 4 is a vertical section taken therethrough substantially on the line 4—4 of Figure 3 looking in the direction of the arrow.

Referring to the drawing in detail it will be seen that the foot rest is adapted to be located in close proximity to the ordinary accelerator pedal 1 which projects through the foot board of the automobile to which

my foot rest is to be attached. This foot rest consists of an integral casting made from any suitable material but I prefer aluminum because of its lightness and attractiveness in appearance. This casting is formed with an elongated body 2 having its sides 3 and 4 extending at right angles from its base 5. The upper surface 6 of the body slants from the side 3 upwardly toward the side 4 and terminates a distance therefrom so that a stop 7 may be provided disposed at an oblique angle to the upper surface 6. A pair of spaced apertured ears 8 extend from the base 5 adjacent the side 3 so as to be disposed preferably one on each side of the accelerator pedal 1. These ears are fastened securely to the foot board of the automobile by screws 9 or some other suitable fastening element. These ears are not only useful in providing attaching means for the body but also provide a wide base for the casting so as to prevent the same from wobbling and with such a wide face caused by the diverging ears 8 which as shown at 75 10 project from the entire length of the base. The end 11 of the upper surface 6 is on approximately the same level with the top of the accelerator pedal 1 when it is in its uppermost position. It will therefore 85 be seen that the edge of the foot will be located at approximately the point 11 on one side while the other side of the foot will rest upon the accelerator and in order to depress the accelerator all that is necessary is 90 to slide the foot toward the end 3.

Having thus described my invention what I claim as new is:—

1. A foot rest of the class described formed from a single casting so as to provide 95 a solid body provided with a slanting upper surface whereby one end is shorter than the other, and a comparatively wide base having apertured ears extending therefrom beyond the shorter end of the body.

2. A foot rest of the class described formed from a single casting so as to include a solid body portion having a slanting upper surface whereby one end of the body is shorter than the other, a stop disposed at 105 the uppermost point of the slanting surface, a comparatively wide base on the bottom of the body portion, and ears diverging from one end of the base beyond the shorter end of the body portion for receiving fastening 110 elements.

3. In combination, an accelerator, a foot

rest associated therewith including a solid body having a slanting upper surface whereby one end of the body is shorter than the other, said surface slanting downwardly to-
5 ward the accelerator, a stop at the uppermost point of the slanting surface, a compara-
tively wide base provided on the bottom of
the body, and diverging ears extending from
one end of the base beyond the shorter end
10 of the body so as to be situated one on each

side of the accelerator, and engaging ele-
ments attached to the ears so as to fasten
them securely to the foot board of an auto-
mobile.

In testimony whereof I affix my signa- 15
ture in presence of two witnesses.

ORLANDO C. FETZER.
